(57) **CLAIM**

The ornamental design for an intraoral sensor, as shown and described.

DESCRIPTION

FIG. 1 is a top, front, right perspective view of an intraoral sensor, in condition of use for clarity of disclosure; FIG. 2 is a top, rear, left perspective view thereof; FIG. 3 is a front elevation view of the intraoral sensor of FIG. 1; FIG. 4 is a rear elevation view thereof; FIG. 5 is a right side elevation view thereof, the left side elevation view being a mirror image thereof; FIG. 6 is a top plan view thereof; and, FIG. 7 is a bottom plan view thereof. The broken lines in the drawings depict portions of the intraoral sensor that form no part of the claimed design. The broken lines showing a cord in FIGS. 1 and 2 depict environmental structure that forms no part of the claimed design. All broken lines form no part of the claim.
